UNITED STATES PATENT OFFICE

HENRY E. LEPPERT, OF NEW BRITAIN, CONNECTICUT, ASSIGNOR TO THE HART MANUFACTURING COMPANY, OF HARTFORD, CONNECTICUT, A CORPORATION OF NEW JERSEY.

ELECTRIC SWITCH.

No. 818,085.

Specification of Letters Patent.

Patented April 17, 1906.

Application filed April 24, 1905. Serial No. 257,127.

To all whom it may concern:

Be it known that I, HENRY E. LEPPERT, a citizen of the United States, residing at New Britain, county of Hartford, and State of Connecticut, have invented certain new and useful Improvements in Electric Switches, of which the following is a full, clear, and exact description.

My invention relates to electrical apparatus, and particularly to electric switches.

It consists, mainly, in improving the means for operating a switch, the same being simple, inexpensive, and effective and capable of operation by a very slight movement.

15 In the accompanying drawings, Figure 1 is a plan view of an electric switch equipped with my improved operating device, the top washer being removed. Fig. 2 is a plan view of the operating device detached. Fig. 3 is a 20 side elevation of the switch, partly in section.

The switches to which my invention relates are termed "snap-switches," as the contact devices are caused to make and break the connection by a very quick or snapping 25 movement. I need not describe in detail the particular construction of such a switch, since there are various forms of the same. I will, however, refer to certain main features.

1 is the base supporting the various parts. 30 2 are terminals.

3 is a contact-blade arranged to make and break the connection with said terminals. The contact-blade 3 is carried on a suitable 35 rotary support 4, which is spring-actuated from a rotatable arbor 5. Mounted on the central arbor 5 is an operating-arm 6, which partakes of an oscillating motion.

7 is a spring arranged to cause the arm 6 to assume a certain normal position.

40 8 is a chain or cord suitably connected with the operating-arm, arranged when pulled to move the operating-arm in opposition to the tendency of the spring 7. When moved in one direction, it is desirable that the 45 operating-arm 6 shall engage with the central arbor 5, so as to rotate the same for the purpose of imparting motion to the contact-blade 3. This engagement is effected by means of one or more independently-moving balls or 50 devices 9, which are arranged in cavities in the inner wall of that part of the operating lever 6 which surrounds the arbor 5. Upon this arbor is preferably fixed a hub 5^a, and these parts 9 are arranged between said hub

5^a and the opposite walls of the grooves in 55 the lever 6. These walls are indicated at 9^a 9^a in Fig. 2, and it will be seen that they are cam-shaped, so that when the operating-arm is turned in one direction the balls will wedge between the lever and the hub 5^a, so that the 60 latter will be clutched and turned with said lever. When, however, the operating-lever is released, it will return freely to its normal position, the balls being freed.

9^b 9^b are springs by which the parts 9 are 63 lightly pressed in a direction to cause them to wedge when the lever is turned in the proper direction.

Suitable washers 10 stand above and below the balls 9 to prevent them from becoming accidentally disengaged.

Neither chain 8 nor spring 7 is necessary for attaining some of the advantages of my invention, as the operating device might be moved directly by hand in both directions. 75

What I claim is—

1. In a snap-switch, a central arbor, a contact device arranged to be operated thereby, an operating device mounted on said arbor, and free to revolve thereon in one direction, 80 and means for engaging said operating device with said arbor when the former is rotated in an opposite direction, said means comprising an independently-moving part arranged between said arbor and the wall of 85 said operating device, said wall being shaped to form a wedge-shaped space for said independently-moving part.

2. In a snap-switch, a central rotatable arbor, a contact device carried thereby, an operating device mounted on said arbor and free to revolve thereon in one direction, and means for engaging said operating device with said arbor when the former is rotated in an opposite direction, said means including 95 a hub, an externally-arranged sleeve-like member overstanding said hub, and an independently-moving part arranged between said arbor and said sleeve-like member and arranged to interlock said sleeve-like member and said arbor when the former is moved in one direction relatively thereto, and a spring for normally pressing said interlocking device toward the interlocking position. 100

HENRY E. LEPPERT.
